UNITED STATES PATENT OFFICE.

GEORGE L. WILLIAMS AND JACOB DUNSTEDTER, OF EDWARDSVILLE, ILL.

GRAIN-BINDER.

SPECIFICATION forming part of Letters Patent No. 279,210, dated June 12, 1883.

Application filed December 15, 1882. (No model.)

To all whom it may concern:

Be it known that we, GEORGE L. WILLIAMS and JACOB DUNSTEDTER, residents of Edwardsville, Illinois, have made a new and useful Improvement in Grain-Binders, of which the following is a full, clear, and exact description, reference being had to the annexed drawings, making part of this specification, in which—

10 Figure 1 is a vertical cross-section taken through the grain-binding mechanism of a harvester having what is known to the trade as the "Appleby Grain-Binder." Only that portion of the binding mechanism is shown as is essential to an understanding of the present improvement. Fig. 2 is a similar section, showing the parts in their position when the deck is depressed; Fig. 3, a plan view with parts of the tables removed, half of the deck removed; 15 and Fig. 4, a view in perspective of the rock-shaft used in operating the compressor-arm and deck.

The same letters denote the same parts in the different figures.

20 The present improvement is especially adapted to what is known as the "Appleby Twine-Binder." In the binder referred to the bundles while being bound lie upon a table and against a compressor-arm, H, and a leaf, B, at the outer edge of the table. Above the bundle is the breast-plate C, for confining the grain and preventing it from being entangled with the band-securing mechanism. To permit the bundle to be discharged from the table the compressor-arm H is withdrawn, the leaf B, which is hinged to the table, is turned down, and the discharging-arms are moved to eject the bundle. Difficulty, however, in practice is experienced from the machine 25 choking. The bundles, especially when large and when the grain is heavy and long, are liable to be caught between the table beneath and the breast-plate and other parts of the binder mechanism above, and sometimes the 30 operation of the binder is entirely arrested by reason of a bundle being wedged above the table, as described. To obviate this difficulty is our present aim. In place of making the table a fixture, and simply withdrawing the compressor-arm and turning down the leaf at the outer edge of the table, the outer portion,

A', of the table or "deck," (as this part is variously called,) is made movable, as well as the compressor-arm and leaf, and while the bundle is being bound the table is upheld; but when it is desired to discharge the bundle the table itself is dropped, as well as the leaf and the compressor-arm, thereby providing more clearance for the bundle, which can now be readily delivered from the machine.

In the drawings, A represents the table; A', the lower or outer movable portion of the table; H, the compressor-arm; B, the leaf, which is hinged to the outer edge, a, of the table A'; C, the breast-plate above the table, and D the cam for operating the movable table, the leaf, and the compressor-arm H.

E represents a shaft, which extends beneath the table and is used in connection with the cam D to operate the compressor-arm, the table, and leaf, the cam moving the lever d, which is connected by means of the spring-rod d' with a crank, e, on the shaft E. A rod, f, leads from the crank f' on the shaft E to the arm b on the leaf B, so that when the cam D depresses the lever d the leaf B is turned down upon its hinges b' b', and when the lever d is raised by said cam the spring-rod d' acts to turn the leaf up again.

The compressor-arm H is pivoted at h, and by means of the link h' is jointed to the crank f', and in consequence of the rotary reciprocating movement of the shaft E the compressor-arm H is raised above and dropped beneath the table A', as shown in the two positions of the arm in Figs. 1 and 2, respectively.

The shaft E is made to serve an additional purpose. The movable portion A' of the table is made so that it can be dropped downward away from the breast-plate and binder mechanism located above it. To this end the table A' may be hinged to the part A, or to any other suitable fixed part, so that it can be depressed when desired below the level of the part A; but the preferable mode of carrying out this part of the improvement is that shown, the table A' being attached by means of the spring-arms a' a' to the support a'.

The shaft E is furnished with the cams e' e', which, when the bundle is being bound, bear up the table A'. When the bundle is to be discharged, the cams are turned to allow the

table A' to drop. The two positions are respectively shown in Figs. 1 and 2, the compressor-arm H being withdrawn and the leaf B turned down when the table A' is dropped, 5 and both being restored to their former position when the table A' is raised.

The shaft E is suitably extended longitudinally beneath the table A' to support cams to act on both ends of said table. The upper table, A, is provided with a depending flange, a², to prevent the grain from passing under it and catching between it and the lowertable, A'.

We claim—

1. An Appleby grain-binder having that portion of the deck which supports the bundle while being bound movable toward and from the breast-plate or other upper confining-surface, and also having the compressor-arm adapted to be raised above and dropped below 15 said deck, for the purpose described.

2. The combination of the movable deck A', the leaf B, the shaft E, having cams e' e', and connecting mechanism for operating said leaf, substantially as described.

3. In a self-binding harvester, the compressor-arm, in combination with the binding-table adapted to be depressed by the pressure and weight of the bundle, means for raising said table and supporting it while the bundle is being formed and bound, and mechanism 25 connected to said raising means, whereby when the latter is operated to permit the table to fall the compressor-arm will be depressed below the table, substantially as described.

GEORGE L. WILLIAMS.
JACOB DUNSTEDTER.
